UNITED STATES PATENT OFFICE

ALBERT M. FREELAND, OF CHICAGO, ILLINOIS, ASSIGNOR TO CARL EDWARD, OF CHICAGO, ILLINOIS

PUMP OR ENGINE

Application filed September 27, 1928. Serial No. 308,785.

This invention relates to improvements in pump or engine particularly adapted, though not necessarily limited in its use, as a compressor or in connection with pressure refrigerating systems and the like, and one of the objects of the invention is to provide an improved engine of the reciprocating type, the pistons and cylinders being reciprocable one with respect to the other, and in which any desired number of co-operating piston and cylinder elements may be employed.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is an irregular sectional view taken on line 1—1, Figure 3.

Figure 2 is a detail sectional view taken on line 2—2, Figure 1, looking in the direction of the arrows.

Figure 3 is a sectional view taken on line 3—3, Figure 1.

Figure 4 is a detail sectional view taken on line 4—4, Figure 2.

Referring more particularly to the drawing the numeral 10 designates a casing of any desired size and configuration and which is provided with an opening 11 in one side thereof and a corresponding opening 12 in the opposite side. The opening 11 is covered by means of a plate 13 while the opening 12 is covered by means of a plate 14, the plates being secured in position respectively by means of suitable fastening bolts 15—16, and packing elements 17—18 are respectively provided between the plates 13 and 14 and the adjacent faces of the walls of the casing so as to form fluid tight joints.

Supported by the plate 13 is a hollow bearing 19 in which a shaft 20 is journaled, the shaft extending through the casing 10 and being also journaled in a bearing 21 carried by the plate 14.

Within the casing and secured to the shaft 20 for rotation therewith is a member 22

which is provided with cylinders 23, any number of which cylinders may be provided and these cylinders are provided with ports 24 adapted to successively register with ports 25—26 in the plate 13 and which plate constitutes a valve plate. A portion of the plate 13 is shaped to form a bearing surface 27 with which a similar bearing surface 28 carried by the member 22 co-operates. The bearing surfaces 27 and 28 are spaced for a considerable distance from the axis of rotation of the member 22, for a purpose to be herein-after set forth.

Reciprocable within the cylinders 23 are pistons 29.

Supported in any suitable manner, preferably by the plate 21, is a cam 30, which cam also encompasses the shaft 20. The axis of the cam 30 is spaced laterally from and inclined to the axis of rotation of the shaft 20, the cam 30 being preferably disposed in close proximity to the member 22.

Encompassing the cam 30 is an element 31 and ball bearings 32—33 may be provided for the element 31. Links 34 which constitute piston rods are pivotally connected by one end as at 35 with the element 31 and the other ends are preferably provided with balls 36 which are pivotally connected with the respective pistons 29.

With this improved construction it will be manifest that when the shaft 20 is rotated the member 22 will be correspondingly rotated and with it the cylinders 23 and pistons 29. The element 31 will also be rotated with the member 22 and as the element 31 rotates about the cam 30 it will cause a reciprocatory movement to be imparted to the pistons in the respective cylinders 23.

In order to hold the co-operating surfaces 27 and 28 of the valve plate 13 and the adjacent face of the cylinders in contact and to provide a fluid tight joint there is provided a collar 37 which is secured to the shaft 20 for rotation therewith and within the bearing 19. A coil spring 38 encompasses the shaft and is also located within the bearing. One end of the spring rests against a portion of the bearing and the other end preferably against a ball bearing 39 which con-

tacts with the collar 37. The stress of the spring 38 is such that it will draw the member 22 toward the plate 13. By arranging the bearing surfaces 27-28 of the plate 13 a considerable distance from the axis of rotation of the member 22, the member 22 will be prevented from tilting with respect to the bearing surface 27 and under the stress of the spring 38.

10 Connected with the port 26 in the valve plate 13 is an outlet opening 40 by means of which the compressed fluid escapes from the cylinders and connected with the port 25 is an inlet port 41 through which the fluid to be compressed is supplied to the cylinders.

15 These ports 25 and 26 are so arranged that as the member 22 rotates the ports or passages 24 in the cylinders will successively communicate first with the port 25 and then with the port 26. During the rotation of the member 22 and as the respective cylinders communicate with the port 25, fluid will be admitted through the inlet 41 into the respective cylinders. As soon as the ports in the respective cylinders pass out of communication with the port 25 the ports in the cylinders will be closed, which will occur just as the pistons start to move towards the ported end of the cylinder so that the fluid will be 20 compressed and this will occur as the ports in the cylinders pass over the unported surface 27 of the valve plate 13. When the ports in the cylinders pass into communication with the port 26, which will occur just before the pistons 29 reach the limit of their 25 inward stroke, the compressed charge will be forced out of the port 26 and through the passage or port 40.

20 If desired an oil groove 42 may be provided in the bearing member 19 which forms communication between the interior of the bearing and the interior of the casing 10 and an oil groove 43 may be provided in a portion of the plate 14 so as to form a means 25 whereby the shaft 20 may be lubricated.

25 In order to vary the distance to which the pistons 29 may move toward the ported end of the respective cylinders, the element 18 may be removed and thicker or thinner similar elements substituted therefor or additional elements 18 may be provided between the plate 14 and the adjacent wall of the casing 10.

30 While the preferred form of the invention has been herein shown and described, it is to be understood that various changes may be made in the details of construction and in the combination and arrangement of the several parts, within the scope of the claims, 35 without departing from the spirit of this invention.

35 What is claimed as new is:—

1. In combination, a drive shaft, a support therefor, a reduced bearing surface connected 40 with the support and encompassing the shaft

a considerable distance from the axis of the shaft, a member connected with the shaft for rotation therewith, ported cylinders carried with said member, a reduced bearing surface on said member contacting with the first recited bearing surface, resilient means operating to maintain said bearing surfaces in contact, pistons in the cylinders, a stationary cam encompassing the shaft, the axis of said cam being spaced laterally from and inclined with respect to the axis of the shaft, an element freely rotatable about the cam and said shaft, and piston rods pivotally connected with said element and the respective pistons.

2. In combination, a casing, one wall of the casing forming a ported valve plate, a shaft extending through the casing, a rotary member within the casing and having cylinders arranged to successively connect with the ports of said plate, pistons in the cylinders, a stationary cam carried by the opposite wall of the casing and in which cam the shaft is journaled, the axis of the cam being spaced laterally and inclined with respect to the axis of the shaft, a member encompassing and rotatable upon said cam, and piston rods connecting the last said member and the respective pistons.

In testimony whereof I have signed my name to this specification, on this 19th day of September, A. D. 1928.

ALBERT M. FREELAND.
